MEANS OF COMMINGLING FLUIDS

William R. Eckart, San Marino, Calif., assignor
to C. F. Braun & Co., Alhambra, Calif., a corporation of California

Application May 16, 1938, Serial No. 208,202

7 Claims. (Cl. 261—114)

This invention relates to liquid-gas contact apparatuses, and particularly pertains to a Means of commingling fluids.

In many chemical, petroleum engineering, and similar processes, the transfer of one or more components from one material to another is involved. Absorption, stripping, fractionation, extraction, drying, etc., may be mentioned as operations requiring such transfer. The transfer from one material to another may or may not include chemical reactions. In such cases, time of contact may be a necessary consideration in the operation of the process. Intimate contact or mixing of the fluids is essential, as these processes depend upon establishing or closely approaching equilibrium relations. In continuously operated processes, multiple contacting of the fluids flowing in a counter-current manner is in general necessarily required. The above-mentioned processes or operations may be conducted in columns of various types containing either packing, perforated trays, or bubble-cap trays.

The present invention relates particularly to the design and use of a novel type of bubble-cap in a column to obtain the required intimacy of contact and to extend the limits or range of such contact and agitation beyond the limits usually established with bubble-caps of ordinary design. The present invention, therefore, permits the use of a lesser number of caps in a given cross-section area of column; allows increased spacing between the caps, thus permitting increased column of liquid flow without building up an excessive hydraulic gradient between the down pipe and weirs, and at the same time, prevents channelling of the downwardly flowing fluid between the bubble-caps and through the trays without contacting the upward flowing fluid.

The present invention contemplates the provision of a bubble-column having an outer shell, a plurality of trays therein upon which liquid may accumulate and from which liquid may pass successively from one tray to another after a desired accumulation has taken place. The trays carry a plurality of caps of novel design and construction which include means for insuring that the gas will be introduced into the liquid flowing across a tray substantially at the bottom of the body of the accumulated liquid on the tray and in a manner to create a maximum amount of agitation in the liquid whereby a high degree of liquid-gas contact will be produced.

The invention is illustrated by way of example in the accompanying drawings in which:

Figure 1 is a view in central vertical section

through a bubble column disclosing the application of the present invention.

Fig. 2 is a view in transverse horizontal section through the bubble column as seen on the line 2—2 of Figure 1, and disclosing the bubble-cap arrangement.

Fig. 3 is an enlarged view in side elevation showing one form of the bubble-cap.

Fig. 4 is an enlarged view in plan showing the bubble-cap disclosed in Fig. 3. 10

Fig. 5 is a view in transverse vertical section through the bubble-cap as seen on the line 5—5 of Fig. 4.

Fig. 6 is an enlarged view in vertical section through another form of the bubble-cap provided with a center bolt. 15

Fig. 7 is a fragmentary view showing a bubble-cap of the present design with a plurality of eductor rings.

Referring more particularly to the drawings, 19 20 indicates the shell of a bubble-column fitted with a bottom closure 11 and a top closure 12, which closures are secured in position in any suitable manner. A gas outlet, pipe 16 communicates with the interior of the column through the top closure 25 12 and permits the upward flowing gas to pass out from the column. Disposed at spaced intervals across the shell, and at different heights therein, are trays 17, upon which oil from an oil inlet conduit 13 may be delivered. These trays are provided with overflow or down pipes 18, one of which is here shown for each tray. 30

By reference to Figure 2 of the drawings, it will be seen that the down pipe there shown represents the segment of a circle. It is to be understood, however, that this sectional formation is not necessarily the only type which may be used, but that in different installations, the down pipes may be arranged and shaped so that they will conform suitably to the design and tray arrangement. It is also to be noted in Figure 2 that the down pipe from super-adjacent trays are shown as being disposed upon diametrically opposite sides of the longitudinal center axis of the shell. In certain installations, this arrangement may be varied to meet the conditions present and to insure the necessary uniform distribution and flow of the fluid over the trays and with relation to each other. Thus, the down pipe arrangement is optional to insure that the liquid will flow across each tray from its point of induction to its point of eduction without channelling and with a maximum intimate commingling action with the gas. The level of the mouth of the upper ends of the down pipes 18, as indicated at 20 acts as weirs 40 45 50 55 60 65 70 75 80 85 90 95 98

and are definitely set to establish the level at which accumulated liquid on a tray will overflow. In some instances, the weir portions may be vertically notched as indicated at 21. The level of the discharge ends 22 of the down pipes 18 are on a plane lower than that of the upper ends 20 of the down pipes associated with the same tray, thus insuring that the down pipes 18 will be liquid sealed at their lower ends, and that the gas passing through the column must pass upwardly through the trays and through bubble-cap units 23.

One form of bubble-cap unit is indicated in Figs. 3 to 5, inclusive, of the drawings. It is to be understood that while the structure there shown represents the preferred form of bubble-cap embodying the present invention, that the cap may be designed differently to accommodate constant or variable velocity flow of fluid.

This cap comprises a tubular riser 24, a bell 25 and an eduction ring 26. The tubular riser extends vertically and has a mouth 27 at its lower end through which gas is introduced. The upper end of the riser is formed with a mouth 28, preferably but not necessarily, of reduced diameter as compared with the lower mouth 27. The lower mouth 27 is formed with a lip portion 29 which extends into an opening 30 formed through a tray 17. A shoulder 31 is formed around the lip 29 and rests upon the upper face of the tray 17. Attention is directed to the fact that the wall of the riser is progressively reduced in thickness from its lower end to the mouth 28, and that the opening 32 which occurs through the riser for the accommodation of the flowing gas progressively decreases in diameter from its influent end to its effluent end. This insures that as the gas flows upwardly through the central passageway 32 of the riser 24 its velocity will be progressively and uniformly accelerated. This acceleration will be continued as the gas passes from the discharge end 28 of the riser, since the bell 25 which extends over the riser and circumscribes the sides thereof, is so designed as to combine with the wall of the riser 24 to form a gas passageway 33 which is progressively restricted in width and area and continues the uniform acceleration of the gas as it flows there along.

The bell 25 is formed with an upper end wall 50 representing an inverted cone, the apex of which is in alignment with the longitudinal center of the riser and which apex projects downwardly with relation to the mouth 28 of the riser to provide a communicating passageway 34 along which the gas may flow from the passageway 32 of the riser to the passageway 33 which is in an enveloping position over and around the riser. It will be understood that the passageway 33 encircles the riser completely, and that it terminates with an annular discharge throat 34' which directs the gas horizontally along the upper surface of a bubble tray 17 and in a plane substantially at right angles to the center axis of the riser. The throat 34' is also progressively contracted 65 in the direction of flow of the gas. The lower edge of the bell 25 is formed with an out-turned lip 35 which substantially follows the contour of the riser 24 and provides clamping means for the bell.

While the bubble-cap structure is here shown as being circular, it is to be understood that the cap may be of any other symmetrical form in order to meet with the problem to be solved in any particular tray arrangement. Various 70 devices differing from those here shown for hold-

ing the assembled parts together may be used to meet the necessity of construction and manufacturing requirements.

Disposed in an encircling position with relation to the bell 25 and its lip 35 is an eduction ring 26. This ring is formed with an outwardly and downwardly flaring wall section 37 which at its upper end stands substantially vertical, and at its lower end is substantially horizontal. An arcuate face 38 is formed by the ring adjacent to the outer face of the bell 25 and its lip 35. This creates a passageway 39 between the ring and the bell which passageway progressively decreases in sectional area in the direction of flow of fluid downwardly and outwardly through it.

The body of the ring is held in spaced relation to the upper face of the tray by a plurality of lugs 40 and 41 which are cast on the underside of the ring and hold the discharge lip 42 of the ring in spaced relation to the upper surface of the tray to create an eduction passageway 43 into which fluids flow from the passageway 39 and the passageway 34', and from which a circumscribing series of radially moving jets will discharge fluids into the body of fluid which has accumulated to a suitable level on the trays.

The rings are provided at diametrically opposite sides with bosses 44 which on their inner sides have overhanging lugs 45. These lugs engage the upper surface of the flange portion 35 of the bells 25 and hold these bells down. The bells are formed at their upper ends with a series of lugs 45' which have an angular seat 46, the horizontal portion of which rests against the upper end face of the riser 24. The lugs 45' rest on the riser 24 and hold the bell 25 with its lip 35 in spaced relation to the riser and the tray. A substantially vertical portion of these lugs extend downwardly over the outside of the riser to center the bell with relation to the riser. Cap 40 screws or bolts 36 extend through the bosses 44 and hold the entire bubble-cap structure in an assembled position over opening 30 in a tray.

Attention is directed to the fact that in this particular construction it is not possible for a 45 riser to fall through a tray in the event that it becomes unfastened, and that furthermore the use of the circumscribing eduction ring and the cap screws make it possible to eliminate a center fastening bolt, which in many instances extends 50 downwardly through the bell 25 and engages a web in the opening 30 over the tray 17 as shown in Fig. 6. This insures that the volume of gas may flow through a bubble-cap without being disturbed or obstructed in its flow until it is 55 projected into the body of liquid within which the bubble-cap structure is partially submerged.

Attention is also directed to the fact that the eduction ring not only holds the bubble-cap assembly in position upon the tray, but that it provides an eduction nozzle through which fluid from the accumulated body of fluid upon the trays may be drawn into passageway 39 and to discharge with the gas through the throat 43, thus 60 acting to recirculate the fluid on the tray in the vicinity of the cap and to bring these fluids into intimate contact with the incoming gas and to create a state of agitation within a body of accumulated liquid on the tray over a large area around the bubble-cap. It will be recognized that 65 this is different from all present known operations of bubble-cap constructions for the reason that here the gas is introduced at the bottom of the accumulated liquid on the tray and in a direction horizontally through the liquid and at 70 75

a velocity greater than that customary in bubble-caps of present design. It will be recognized further that the high velocity of the gas or vapor will create a jetting action which not only will 5 disturb the accumulated liquid throughout its entire height, but will recirculate the mixed fluid continuously as the operation proceeds insuring intimate action, not only in the vicinity of the cap, but in the liquid between the caps which 10 may be spread further apart than ordinarily.

The present invention makes possible an entirely new spacing arrangement of the down pipes and bubble-caps of any particular tray. As will be hereinafter pointed out, the bubble-caps here 15 described may be widely separated from each other to accommodate large volumes of liquid which flow across the trays and between the caps without building up an excessive hydraulic gradient. This is essential in order to prevent the 20 hydraulic gradient from building up on a tray due to increased velocity between bubble-caps which would cause the depth of liquid at successive rows of caps to be varied, with the result that the gas would then flow through the caps having the least submergence and gas would not 25 flow through the caps having greater submergence, due to the increased pressure head of the greater depth of liquid.

By use of the bubble-cap structure here shown, 30 and by the spacing which is provided, a substantially uniform hydraulic gradient is maintained on each tray and thus an efficient degree of contact is established between the commingling fluids, while insuring that maximum 35 volume of said fluids desired may pass through the column. It is to be pointed out that heretofore in bubble-cap arrangement, the gas was merely discharged into the body of liquid accumulated upon a tray and liberated from substantially vertical slots in the lip of the bubble-cap at a level materially above that of the floor surface of the tray. In addition the ordinary caps are generally set at a distance above the tray of from $\frac{1}{4}$ " to $\frac{1}{2}$ " to allow 40 for any accumulation of deposits of sludge on the tray without interference with the openings of the cap slots. Thus with this arrangement the effective gas passageways will occur in the center of the body of accumulated liquid and at 45 50 a level materially above the surface of the tray. This will produce channelling of the liquid. With such bubble-caps of ordinary design and with a given depth of liquid on the tray substantially determined by the weir height and 55 perimeter the depth of gas discharge below the liquid surface, the time of contact between liquid and gas, the depth of liquid contacted by the gas, and the degree of agitation, the pressure drop through the liquid will vary with the 60 volume of gas flow. Therefore the efficiency of the tray is affected by all of these variables. Such caps are generally designed to have the gas discharge throughout the whole depth of the cap-slots at full or maximum load. Even 65 then there is a body of liquid flowing across the tray below the bottom of the cap-slots which is not contacted at all by the gas.

It is manifest that with the use of the bubble-cap here shown, the gas is discharged at high 70 velocity and directed along the floor of the trays under a condition of maximum hydraulic head. The entire area of liquid occurring between neighboring bubble-caps will be agitated throughout to insure a maximum commingling 75 of the gas and liquid and there will not be a

tendency for the liquid to channel, since the gas is projected at all rates of flow entirely along the floor of the tray. It will further be apparent that there will be more time of contact between the fluids, and a more violent and uniform agitation of the fluids. It will also be recognized that since the center of the gas pressure below the liquid surface is always substantially constant in each bubble-cap for a given height of liquid on its tray, and that the passageways through 10 which the gas will flow are stream-lined to reduce friction and eddy losses to a minimum, the total pressure drop through the bubble-cap assembly and the liquid will vary primarily only 15 with the velocity of the gas flow. This is contrary to the condition in the ordinary cap where the center of pressure below the liquid surface increases as the velocity of gas increases, so that the head of liquid through which the gas must rise also increases. Furthermore, the increased 20 velocity with which the gas is discharged and the fact that it always issues from the bubble-cap, close to the floor of the tray, will prevent any possible accumulation of deposits such as 25 gum, sludge, solids, and other foreign material, around the discharge opening and upon the trays, thus insuring against clogging of the apparatus.

Referring particularly to the form of the invention shown in Fig. 6, it will be seen that a 30 riser 41 is provided having a shoulder 43 which engages the under face of a tray 17. The inside of the bell of the cap 50 has fins which center the bell relative to the riser. The bell 50 which extends down over the riser and is formed at its outer edge with a lip 51 here shown as resting on a shoulder 52 of a rib 53 on an eduction ring 54 to hold the eduction ring 54 in place. A bolt 55 extends downwardly through the bell 50 and through a web bearing 56 to hold 40 the entire structure assembled and to secure it with relation to the tray 17. In the form of the device shown in Figure 7 a plurality of eduction rings 54 are provided nested one within the other and disposed around the marginal edge 51 of the 45 bell.

In operation of the present invention gas is delivered into the bottom of the shell 16 through a gas delivery pipe 58. The gas inlet is always above the liquid level maintained in the bottom 50 of the bubble column, and above the liquid outlet. An oil draw-off pipe 57 also connects with the bottom portion of the shell at a level below the gas inlet pipe 58. Liquid is then fed into the upper end of the shell through the conduit 13 and will accumulate upon the trays until all of the trays are covered with liquid to a 55 desired level.

Due to the violent agitation produced by the 60 gas introduced into the liquid at higher velocity than at present customary, it is evident that intimate contact of the gas and liquid will be created over a much larger area than is now usually the case, thus making it possible to place the bubble-caps at greater distance from each other than is now common without decreasing the efficiency of the apparatus and without possibility that the liquid will channel between the caps without intimately contacting the gas. It 65 will also be evident that a violent agitation of the liquid will be created and that the action of the eductor rings will cause the liquid lying immediately around the cap to be drawn in by aspiration and to be discharged with the gas at the eductor slots 43. Such liquid contacting 70 75

the gas passing through the eductor ring will be maintained in intimate contact over a longer period of time than is now usual, thus insuring a more efficient action. The gas passes upwardly through the center passageway 32 of the riser as indicated by the arrow A in Fig. 5 and it will be discharged into the mouth 28 and will be deflected into the inverted cone shaped top of the bell 25, thereafter passing around the lip 5 of the riser as indicated by the arrow b in Fig. 5, and then downwardly along the passageway 33 to be discharged from the bell 25 at 34' into the passageway 43 of the eduction ring and to pass along the surface of the tray 17 as indicated by 10 the arrow c. At the same time fluid from the body of liquid will be drawn in through the passageway 39 as indicated by the arrow d in Fig. 5 and will commingle with the gas which is passing outwardly through throat 34'. All of 15 the surfaces along which the gas passes have been stream-lined to reduce loss of pressure head as might occur due to sudden change of section of the passageway, direction of flow, expansion of gas and eddying of the gas as it flows. Attention is directed to the fact that the mouth 27 of the riser is curved with relation to the tray 17 so as to be well rounded or bell mouthed and to bring the inflowing line of gas flow relatively close to the undersurface of the 20 tray as indicated by the line x. This permits minimum contraction of the stream and prevents losses due to eddying of the gas from cavitation as it flows into the riser. Gas will thus flow in a smooth even stream accelerating progressively from the induction end of the opening 25 27 of the riser to its point of discharge through the throat 43. As the gas rises through the caps and contacts the liquid on the successive trays multiple action occurs, the number of trays 30 and contacts being determined for the particular operation being performed and the degree of equilibrium to be established.

The eductor rings 26 are provided with lugs 48 and 49 to break or divide the gas stream in 45 a horizontal plane into separate lines of gas in a manner similar to that accomplished by vertical slots in ordinary bubble-cap construction. This insures breaking up of bubbles and a high degree of intimate contact of the gas 50 with the liquid when it is discharged from the ring. The eductor rings also serve the purpose of causing the gas flowing from the bell to induce the liquid above the cap to enter and commingle with the gas during its passageway 55 through the eductor ring. Thus the gas which passes downwardly and outwardly through the passageway 33 and the throat 34' will draw liquid downwardly through the throat 39 and cause this liquid to commingle with the gas, at the bottom 60 of the accumulated mass of liquid on the tray and along the surface of the tray. It will also be evident that as the gas and the liquid discharge from the eductor ring a disturbance of the liquid will be created above and outside of 65 the eductor ring and in the general direction of gas flow. This insures that the entire accumulated body of liquid upon the tray will be disturbed and agitated, thereby producing a maximum intimate contact between the gas and the liquid particles. In the use of the structure shown in Fig. 7 where a plurality of eductor rings 54 are provided, it will be evident that the range of agitation and recirculation of the fluids 70 will be extended. It will further be recognized 75 that eductor rings of the type here disclosed

might be used in conjunction with other types of bubble-caps in which the gas is ejected therefrom beneath a submerged lip, thus obtaining a degree of agitation and commingling of the fluids not now possible. It is also to be understood that the shape and design of the bubble-caps and eductor rings may be varied in order to meet a particular problem in liquid-gas contact, and that the caps may be designed to determine and control the velocity of fluids through the apparatus. For example when the caps are designed for increasing velocity through the passages the cross-sectional area of the caps are arranged so that even with the same spacing as with ordinary caps they will insure that a greater volume of liquid may pass between the cap with the same hydraulic gradient as compared with ordinary caps of the same diameter.

It will thus be seen that the bubble-cap structure here disclosed provides means readily adaptable in design to meet any problem which might arise in liquid-gas contact apparatus, both as to the character of the products to be commingled and as to the velocities and pressures under which they flow, and that by the arrangement here shown an increased commingling action will result as compared with the ordinary bubble-caps.

While I have shown the preferred form of my invention and the preferred method of practicing the same, it is to be understood that various changes might be made in the combination, construction and arrangement of parts and various changes in the steps of the method without departing from the spirit of my invention as shown and disclosed. It will be understood that while certain elements have been described as being tubular and are shown as being circular in cross-section that they may be of any cross-sectional shape desired without departing from the spirit of the invention.

Having thus described my invention, what I claim and desire to secure by Letters Patent is:

1. A bubble column comprising a shell, a tray 45 therein upon which liquid may accumulate to a desired level, said tray being formed with an opening therethrough, a bubble cap mounted over said opening formed with a central tubular riser through which a gas may flow upwardly and circumscribed by a cap spaced from the 50 tubular riser and through which said gas may flow downwardly and be projected outwardly in a path of travel substantially parallel to the plane of the upper surface of the tray and beneath the body of liquid accumulated thereon, the passageway within the bubble cap and through which the gas flows being progressively constricted in sectional area and an eduction ring circumscribing the bubble cap in the area 55 of gas discharged therefrom, said ring providing a throat through which the accumulated liquids 60 upon the tray may be drawn by the discharging gas and commingled therewith.

2. A bubble cap structure adapted to be mounted over an opening in a bubble column tray upon which tray an accumulated body of liquid occurs, which structure comprises a riser mounted over said opening, said riser being tubular and having openings at its opposite ends, the passageway through the riser progressively decreasing in diameter from its influent to its effluent end and a bell element fitting over the effluent end of the riser and extending downwardly to a joint adjacent the face of the tray upon which the riser 75

is disposed, the bell being spaced with relation to the outside of the riser and the surface of the tray whereby a fluid space will occur to receive fluids from the riser and to direct said fluids downwardly and then outwardly along the upper face of the tray, the said downwardly and outwardly directing fluid passageway being progressively reduced in sectional area in the direction of the flow of fluid, an eduction ring 10 scribing the lower circumference of the bell and having a wall spaced therefrom and conforming substantially thereto and extending outwardly therebeyond whereby a throat will be formed between the lower portion of the bell and the eduction ring to direct fluid into the stream of liquid passing from the space between the eduction ring and the riser, said throat being reduced in sectional area progressively in the direction of flow of fluid.

20 3. A bubble cap structure adapted to be mounted over an opening in a bubble column tray upon which tray an accumulated body of liquid occurs, which structure comprises a riser mounted over said opening, said riser being tubular and having unobstructed openings at its opposite ends, the passageway through the riser progressively decreasing in diameter from its influent to its effluent end and a bell element fitting over the effluent end of the riser and extending downwardly to a point adjacent the face of the tray upon which the riser is disposed, the bell being spaced with relation to the outside of the riser and the surface of the tray whereby a fluid space will occur to receive fluids from the riser and 35 to direct said fluids downwardly and then outwardly along the upper face of the tray, the said downwardly and outwardly directing fluid passageway being progressively reduced in sectional area in the direction of the flow of fluid, and eduction ring circumscribing the lower circumference of the bell and having a wall spaced therefrom and conforming substantially thereto and extending outwardly therebeyond whereby a throat will be formed between the lower portion of the bell and 40 the eduction ring to direct liquid into the stream of fluid passing from the space between the eduction ring and the riser, said throat being reduced in sectional area progressively in the direction of the flow of fluid.

50 4. A bubble cap structure adapted to be mounted over an opening in a bubble column tray and upon which tray an accumulated body of liquid occurs, which structure comprises a riser mounted over said opening, said riser being tubular and having openings at its opposite ends, the passageway through the riser progressively decreasing in diameter from its influent to its effluent end and a bell element fitting over the effluent end of the riser and extending downwardly to a point adjacent the face of the tray upon which the riser is disposed, the bell being spaced with relation to the outside of the riser and the surface of the tray whereby a fluid space will occur to receive fluids from the riser and to direct said fluids downwardly and then outwardly along the upper face of the tray, the said downwardly and outwardly directing fluid passageway being progressively reduced in sectional area in the direction of the flow of fluid, an eduction ring 55 circumscribing the lower circumference of the bell and having a wall spaced therefrom and conforming substantially thereto and extending outwardly therebeyond whereby a throat will be formed between the lower portion of the bell and the eduction ring to direct fluid into the stream of liquid passing from the space between the bell and the riser, said throat being reduced in sectional area progressively in the direction of flow of fluid, and a plurality of additional eduction 60 rings circumscribing the first mentioned eduction ring and being disposed concentric to each other in the horizontal plane thereof, said rings having cooperating faces to form a downwardly and outwardly directed passageway through which fluid 65 may be directed into the jet of the fluid flowing from beneath the first mentioned eduction ring.

70 7. A bubble column comprising a shell, a tray therein, a riser extending upwardly from the tray and having an unobstructed passageway there- 75

tion ring to direct liquid into the stream of fluid passing from the space between the bell and the riser.

5 5. A bubble-cap structure adapted to be mounted over an opening in a bubble column tray and upon which tray an accumulated body of liquid occurs, which structure comprises a riser mounted over said opening, said riser being tubular and having openings at its opposite ends, the passageway through the riser progressively decreasing in diameter from its influent to its effluent end and a bell element fitting over the effluent end of the riser and extending downwardly to a point adjacent the face of the tray upon which the riser is disposed, the bell being 15 spaced with relation to the outside of the riser and the surface of the tray whereby a fluid space will occur to receive fluids from the riser and to direct said fluids downwardly and then outwardly along the upper face of the tray, the said 20 downwardly and parallel directing fluid passageway being progressively reduced in sectional area in the direction of the flow of fluid, an educting ring circumscribing the lower circumference of the bell and having a wall spaced therefrom and 25 conforming substantially thereto and extending outwardly therebeyond whereby a throat will be formed between the lower portion of the bell and the eduction ring to direct liquid into the stream of fluid passing from the space between the bell 30 and the riser, and means whereby the eduction ring may be secured to the tray to hold the riser and the bell in assembled operative relation thereon.

6. A bubble-cap structure adapted to be mounted over an opening in a bubble column tray and upon which tray an accumulated body of liquid occurs, which structure comprises a riser mounted over said opening, said riser being tubular and having openings at its opposite ends, the passageway through the riser progressively decreasing in diameter from its influent to its effluent end and a bell element fitting over the effluent end of the riser and extending downwardly to a point adjacent the face of the tray upon which the 45 riser is disposed, the bell being spaced with relation to the outside of the riser and the surface of the tray whereby a fluid space will occur to receive fluids from the riser and to direct said fluids downwardly and then outwardly along the 50 upper face of the tray, the said downwardly and outwardly directing fluid passageway being progressively reduced in sectional area in the direction of the flow of fluid, an eduction ring circumscribing the lower circumference of the 55 bell and having a wall spaced therefrom and conforming substantially thereto and extending outwardly therebeyond whereby a throat will be formed between the lower portion of the bell and the eduction ring to direct fluid into the stream of liquid passing from the space between the bell and the riser, said throat being reduced in sectional area progressively in the direction of flow of fluid, and a plurality of additional eduction 60 rings circumscribing the first mentioned eduction ring and being disposed concentric to each other in the horizontal plane thereof, said rings having cooperating faces to form a downwardly and outwardly directed passageway through which fluid 65 may be directed into the jet of the fluid flowing from beneath the first mentioned eduction ring.

7. A bubble column comprising a shell, a tray therein, a riser extending upwardly from the tray and having an unobstructed passageway there- 75

through, a bubble cap positioned over the riser and in spaced relation thereto, the lower marginal lip of the cap being adjacent to the face of the tray above which it is mounted and forming an annular passageway beneath the level of the accumulated liquid upon the tray, and an eduction

ring mounted upon the face of the tray and circumscribing said passageway, said ring being spaced from the outer surface of the cap and forming a downwardly and outwardly direct passageway between and around the bubble-cap.

WILLIAM R. ECKART.
